UNITED STATES PATENT OFFICE

162,783

PORTABLE TONSORIAL CABINET

Leon Budny, Cheektowaga, and Edward F. Gornikiewicz, Buffalo, N. Y.

Application December 17, 1948, Serial No. 150,206

Term of patent 14 years

(Cl. D33—19)

To all whom it may concern:

Be it known that we, Leon Budny and Edward F. Gornikiewicz, both citizens of the United States, residing at Cheektowaga and Buffalo, respectively, in the county of Erie and State of New York, have invented a new, original, and ornamental Design for a Portable Tonsorial Cabinet, of which the following is a specification, reference being had to the accompanying drawings, forming part thereof.

In the drawings:

Fig. 1 is an elevational view of the front side of a portable tonsorial cabinet embodying our new design.

Fig. 2 is an elevational view of the left end thereof.

Fig. 3 is an elevational view of the right end thereof.

Fig. 4 is a top plan view thereof.

Fig. 5 is an elevational view on a slightly reduced scale, of the rear side thereof.

Fig. 6 is an enlarged perspective view thereof and showing the cover raised to expose the interior of the cabinet and also showing the drawers on the front side thereof partially opened.

Fig. 7 is a top plan view, on a reduced scale, of the cabinet shown in Fig. 6, the drawers being shown as fully closed.

We claim:

The ornamental design for a portable tonsorial cabinet, as shown.

LEON BUDNY.

EDWARD F. GORNIKIEWICZ.
